ASSIGNORS TO MELLOR BROMLEY & COMPANY LIMITED, OF LEICESTER, ENGLAND,
A BRITISH COMPANY

PATTERNING MECHANISM FOR KNITTING MACHINES

Application filed January 16, 1930, Serial No. 421,687, and in Great Britain February 16, 1929.

This invention relates to patterning mechanism for knitting machines, and concerns mechanism of the kind which has a selective action upon elements of the machine for producing pattern effects in the knitted fabric.

The object of the invention is to produce an improved form of patterning mechanism capable of being applied for operating selectively upon various elements and is itself capable of variation for changing the pattern produced.

To enable the invention to be clearly and readily understood, we will describe, with reference to the accompanying drawings, some constructional forms of the improved pattern mechanism, such as may be used for example in a circular knitting machine wherein slidable needles are actuated by jacks thereunder.

20 In the drawings,

Figure 1 is a plan view and

Figure 2 is a side elevation of one form of the invention.

Figure 3 is a sectional view of a needle cylinder and one of the selecting members in the active position but inoperative upon the opposing jack.

Figure 4 is a view similar to Figure 3 but shows the selecting member acting upon an opposing jack.

Figure 5 is a plan view and

Figure 6 is a part sectional elevation of a modified form of the invention.

Figure 7 is a view per se of a modified form of needle jack hereinafter particularly referred to.

Figures 8 and 9 illustrate modifications concerned with a controlling drum described later herein.

40 Figure 10 is a developed view of the cam system employed in combination with the pattern mechanism.

Figure 11 is a plan view of two of the cams employed in said system.

45 Figure 12 is a sectional plan view of the cams shown in Figure 10.

Figure 13 is a sectional elevation taken on line XIII—XIII of Figure 12.

50 Figure 14 is a sectional elevation taken on line XIV—XIV of Figure 12.

Figure 15 is a side elevation of the head of the circular knitting machine showing how that form of the invention illustrated in Figures 1 and 2 is applied to the machine.

Figure 16 is a side elevation of one form of the invention adapted for selective action upon sinkers or web holders.

Figure 17 is a part sectional end elevation of a flat machine showing a form of the invention applied thereto and

Figure 18 is a view looking in the direction of the arrow in Figure 17.

The improved mechanism is mainly intended for application to circular knitting machines having slidable needles, but it may be applied to any type of circular knitting machine either latch or beard needle, also to straight-bar and other machines; in fact the pattern mechanism constituting this invention is to be regarded as a master mechanism, applicable to knitting machines in general, for acting selectively upon needles, sinkers, web-holders or other elements for producing pattern effects in the fabric as it is knitted.

The said pattern mechanism comprises a series of rotary members formed or adapted to have selective action upon the elements of the machine which are to be controlled or influenced, said rotary members being movable individually into and out of action preferably under pattern control.

By the expression "rotary members" we mean discs, rings, wheels and the like pattern members, as will be hereinafter set forth.

The said series may comprise two or more of the rotary members referred to, the important or characteristic feature of the invention being that members in the series are individually movable into and out of operation.

The pattern mechanism may consist of a number of selecting members each supported by a separate carrier adapted for movement whereby its member can be moved to and from an operative position, the movement of the carriers being imparted or controlled by a pattern device so that the associated members are rendered operative and

inoperative in predetermined manner according to the pattern effect to be produced.

In such arrangement the selecting members may themselves be selectively controlled, that is to say, the pattern device or means provided for rendering the said members operative and inoperative may act selectively upon the series.

In the main it is intended to carry out the invention in a form suitable for application to circular knitting machines for acting selectively upon instrumentalities such as needles, jacks, sinkers, or the like, in which case the selecting members may conveniently take the form of discs, wheels or like means having peripheral formations or elements for engagement with said instrumentalities. It is to be understood however that the said member may vary as regards form and likewise as regards manner of mounting and movement.

The rotary members are preferably positively driven so that the drive is not interfered with by their movement into and out of action and consequently their register with the instrumentalities is maintained while out of action. The said members are also preferably removable and interchangeable with others for changing the pattern. The members themselves may be variable for producing different effects.

According to a convenient practical embodiment of the invention, applicable for use in circular knitting machines having slideable needles, the patterning mechanism comprises a series of rotary selecting members in the form of discs or wheels having notched peripheries for acting upon the needles or jacks employed therewith.

40 The discs or wheels are mounted independently of each other so as to be individually movable into and out of engagement with the needles or jacks.

45 Each disc or wheel is carried by a swinging or slideable plate capable of movement in a radial or substantially radial direction to enable the disc or wheel to be displaced bodily in relation to the needle cylinder, whereby it may be rendered operative and inoperative. 50 The movements of the swinging or slideable plates for the purpose aforesaid are obtained by spring means, and a cam drum or some similar pattern controller. Preferably the carrier plates are spring controlled to hold the discs in an inoperative position and are moved by a cam drum or equivalent to carry the discs into engagement with the needles or their jacks.

55 The discs are positively rotated by mechanism which ensures maintenance of register between the peripheries of the discs and the needles or jacks of the machine so that, when the discs are moved to the operative position, they will properly mesh with the instrumen-

talities of the machine which they are to influence.

Conveniently, for this purpose, the discs or wheels are driven by a common member such as a pinion or driving rod or key arranged in such relation to the discs that movement of the latter to and from the operative position can occur without disengagement of the said discs from the driving member.

70 The discs may be directly driven by the pinion, rod or key, but it is preferred to provide the carrier plates with a rotary part, such as a wheel or ring, which is driven by the driving member and to which the discs are applied in a removable manner so that they may be interchanged with others having different peripheral formations for the purpose of changing the pattern effect produced 75 in the knitted fabric.

In the arrangement just described the carrier plates may be suitably stacked so as to move independently of each other, and, for putting the various discs or wheels into operation in pre-arranged manner, the cam drum or equivalent device for acting upon the plates may have cams or projections suitably distributed for acting in desired order. This cam drum or equivalent may be operated by ratchet or other mechanism, and this 80 may be controlled by pattern means.

85 According to the form illustrated in Figures 1 and 2, the pattern mechanism comprises a series of plates 1 stacked one above another and slideable towards and from the needle cylinder 2 in vertical guides 3 carried by a bracket 3a and having grooves 4 cut therein for the reception of the plates. Inserted in each of the plates 1 is a rotatable ring 5 formed with a flange 6 which rests on the plate and has peripheral notches 7 for engaging jacks 8 in the needle cylinder 2. Each ring is readily removable for replacement by another having different peripheral formations.

90 The plates 1 are controlled by springs 10 which act to move the plates away from the needle cylinder while the movement of the plates in the opposite direction is imparted by pins or projections 11 inserted in a controlling drum 12, so as to act upon opposing projections 13 on the plates. In this manner the pattern rings are moved towards and from the needle cylinder in accordance with the prearrangement of the pins or projections 11 in the drum.

95 Rotation is imparted to the rings 5 by means of a rod or key 14 fixed vertically in the hub of a pinion 15 so as to extend through the series of rings each of which has formed therein an open ended slot 16 extending radially from the inner edge for engagement by the rod or key as indicated in Figure 1. The rod or key follows a circular path and, by working in the slots as aforesaid, causes the 100

5 rings 5 to rotate in the plates 1. The radial slots are of a sufficient length to allow the bodily movement of the plates and rings to take place, which movement is preferably timed to occur when, during the rotation of the rings, the slots therein assume a position in line with the direction of movement of the slideable plates. The pinion 15 meshes with a toothed ring 15a on the needle cylinder 2 so that the rings 5 are driven in proper ratio with the cylinders, the directions of rotation being shown by arrows in Figure 1.

10 In another constructional form (Figures 5 and 6) the rotary selecting members are carried by plates or arms 1a stacked one above another on a rod or post 17 fixed in a bracket 3b, said plates or arms being movable pivotally into and out of the operative position as and when required. Each plate has rotatably mounted therein a ring 5a furnished with internal teeth 16a and serves to carry removably a disc 6a having a peripheral formation for engaging the aforesaid jacks 8. The disc 6a is engaged by pins or pegs 18 in the ring 5a so that it is driven thereby and can be readily removed and replaced by another having a different peripheral formation. Alternatively the ring 5a may be formed to serve as a selecting member, the disc 6a being dispensed with.

15 The plates or arms 1a are capable of sufficient swinging movement on the post 17 to carry the discs into and out of contact with the jacks 8 and are moved towards and away from the jacks by a controlling drum and spring arrangement similar to that already described with reference to Figures 1 and 2.

20 The drive is imparted to the rings 5a by a long pinion 14a which passes through the centre of the series and engages with the internal teeth of the rings 5a. The pinion is so positioned that, while maintaining its mesh with the internally toothed rings 5a it allows the plates 1a to have the necessary movement for carrying the discs 6a into and out of engagement with the jacks 8. The pinion is attached to a gear wheel 14b which in turn is driven from a gear ring 19 on the needle cylinder through intermediate pinions 20, 21 and 21a, the directions of rotation being indicated by arrows.

25 In this, as in the previously described construction, the rings are continuously driven and the movement of the carrier plates takes place horizontally so that the discs or rings move substantially radially into and out of operative position.

30 While in Figure 6 only a few of the discs 6a and plates 1a are shown, it will be understood that a full bank of these elements will be provided, one supporting another. In the construction shown in Figure 2, however, a full bank of plates or discs may or may not be provided according to requirements.

35 In the constructional forms just described,

the rotary rings or discs are notched at their periphery and their action upon the jacks of the knitting machine is a selective one for the purpose of causing certain of the jacks to function in a different manner from the others. The jacks are projected outwards radially as they approach the series of selecting discs, and those jacks which register with notches in the peripheries of the rings or discs remain in their outwardly projected position as indicated in Figure 3, while those which register with the unnotched periphery of the rings or discs are thereby pressed inwards, as represented in Figure 4. In this manner there is a selection of the jacks which enables one group to function in a different manner from another. For example, the jacks which are not pressed inwards by the selector rings or discs may engage with an incline 22 (Figures 3, 4, 10 and 12) and thereby be raised so that the corresponding needles are raised as represented at A Fig. 10 to clear. The jacks which are pressed inwards by the selector rings or discs avoid engagement with the incline 22 so that the corresponding needles remain at a low level as represented at B in Fig. 10 and either miss the yarn or tuck. The jacks may be projected outwards by cam or other means. The outward projection of the jacks may be effected by giving them a canting movement. We find it convenient to employ jacks having an upper extremity 8a of hooked formation, the hook ends engaging a cam 23, Figure 10, suitably positioned and shaped as shown in Figures 11, 12, 13 and 14 to move all the jacks radially outwards prior to selection. The incline 22 is engaged by the hooked ends 8a of those jacks which remain projected after passing the rings or discs as shown in Figs. 3 and 12, while the hooked end of the jacks, which are pressed inwards as aforesaid avoid engagement with the incline 22 as shown in Figures 4 and 12, with the result previously explained. The jacks are retained in the needle tricks at their lower ends by a ring or band 24, the inner side of which is slightly inclined as shown in Figures 2, 13 and 14 to permit of the aforesaid canting movement of the jacks. A

40 cam 22a having a sloping face as shown in Figures 11 and 12 ensures that all the jacks are pushed inwards preparatory to engagement with the cam 23.

45 As already mentioned, for operating upon the jacks the required number of plates and their rings or discs are disposed horizontally and are stacked or piled one above another. It will be understood that when the different rings or discs are put into operation, they will engage with different parts of the jacks, which latter are made of sufficient length to embrace the whole series of rings or discs. The important feature of this pattern mechanism is that the carrier plates are all indi-

ividually movable and are moved selectively by the controlling drum or by an equivalent controlling device, which drum or device is so designed or arranged that any one or 5 more of the selecting rings or discs can be brought into action as and when required. Said controlling drum or equivalent also controls the time during which the one or more discs remain in operation and, as previously 10 mentioned, this drum or equivalent may itself be controlled by mechanism of any appropriate kind.

Preferably, the controlling drum consists of a cylinder or sleeve carrying pins or projections as aforesaid, said pins or projections being removable so that their positions can be changed from time to time. The pins may be screwed into holes 11a in the drum, or may be held therein such as by nuts. 15 20 Preferably, however, the pins are pushed into the holes and are held in position by a cylindrical sleeve or tubular member 12a suitably carried from the bracket 3a, and furnished with a slot 12a see Fig. 6, through 25 which the pins 11a are exposed for action upon the plates. According to the construction shown in Figure 8, each pin 11 has a shoulder 11b up to which the pin is inserted in the drum. Alternatively, as shown in Figure 9, each pin is of uniform diameter and a sleeve 12b is fitted tightly in the drum to form a stop for the pins. In another construction pins of a form similar to that shown in Figure 8 may be inserted from the inside 30 35 of the drum, and a sleeve may be inserted in the drum for contact with the pin heads so as to take the endwise thrust when the pins act upon the plates as aforesaid.

The drum or cylinder is racked round intermittently by a pawl 25 and ratchet wheel 26, the pawl being controlled in its action, i. e. disengaged from or allowed to engage the ratchet wheel 26, by a bluff device which consists of an annular member 27 surrounding the ratchet wheel and furnished with an opening 27a through which the pawl engages the ratchet wheel. The bluff member 27 has suitably imparted thereto a slight rotary or oscillatory movement when required to 40 45 50 move and hold the pawl clear of the wheel. The pawl, which is spring controlled, is pivotally mounted on a spring controlled lever 28 operated by a cam 29 on or rotating with the needle cylinder. The lever may carry 55 on its free end a roller 30 or equivalent for engagement by the cam.

Figure 15 shows the application, to a circular knitting machine, of the mechanism described with reference to Figures 1 to 4, the 60 bracket 3a being attached to the bed plate a of the machine by means of the screws b. The pattern discs or wheels act upon the aforesaid jack through an opening c in the cam box d. Similarly when the mechanism shown in Figures 5 and 6 is used the bracket

3b is attached to the bed plate a so that the discs or wheels 1a operate through the opening c.

Where the carriers are stacked or arranged one above another, the construction and arrangement may be such as to enable said carriers to be readily removed or moved to a position to enable the selective members to be changed.

In the construction where swinging carrier plates or arms are arranged on a fulcrum post, the said plates may be removable therefrom to enable the discs to be changed. In the other construction described the slideable carrier plates are held in position by a plate 31 which is attached to one of the supporting pillars 3, so that it can be moved to one side to enable the plates to be extracted. Alternatively the plates may be supported and guided by flanged collars on the supporting pillars, the said collars being removable or rotatable to enable the plates to be removed for changing the discs.

In the construction where the carrier plates have a swinging or oscillating movement we may adopt the form of drive herein described with reference to the slideable carrier plates, i. e. the form including a rod or key.

The invention is not to be confined to the use of the improved pattern mechanism for producing patterns by any particular method, as it may be employed for producing patterns by almost any known method. For instance instead of arranging for the pattern mechanism to act upon jacks as aforesaid, said mechanism may, as represented in Fig. 16, be arranged for selective action upon sinkers or web-holders 32.

While discs or wheels having notched peripheries are convenient for obtaining the desired selective action upon the instrumentalities of the machine, it is to be understood that we may use in the improved pattern mechanism selective members of other form, for example, we may employ rotary devices carrying bits or elements such as 6b (Figs. 19 and 20) or such as 6c (Figs. 21 to 23) for engaging the instrumentalities.

Provision may be made for knitting patterned fabric on a portion only of the needles. For example when jacks 8 are employed each of those employed with the non-patterning needles may be formed with a recess 8b, as shown in Figure 7, so as to enable same to avoid contact with the selecting members when the latter are rendered operative as previously described herein. The other jacks i. e. those associated with the patterning needles are not recessed and therefore are acted on by the selecting members as previously explained. In this way the majority of the needles e. g. two thirds or some other fraction of the whole, are allowed to knit ordinarily while the remainder produce

the pattern in the required portion of the fabric. An arrangement of this kind may be adopted when patterns are to be produced by means of yarns of different colours in which case a plain non-gapped disc or member may be provided in association with the bank or each bank of selecting members for prearranged movement into the operative position so as to engage the recessed jacks, either below or above the recesses, and push same inwards and thereby cause the corresponding needles to miss one of the yarns at the feeder or at any desired feeder when there are more than one. To prevent operation of the remaining jacks by this member each of these jacks is provided with a notch which registers with the pattern member and is entered by same when the latter is in the operative position.

20 In lieu of the construction and arrangement aforesaid two or more cams such as 29 may be located at predetermined points around the needle circle in conjunction with appropriate prearrangement of the pins, 25 pegs or other elements in the controlling drum or equivalent, so that one cam serves to put the required selecting member or members into operation, and the other or another determines the withdrawal of the said member or members.

It will be further understood that the discs or selective members comprising the series have peripheral or operative formations which contrast with each other, so that different pattern effects are produced when the different members are put into operation.

In applying the invention to a straight-bar or flat machine, the bracket 3* for the carrier plates 1 and drum 12 may be mounted on the cam box 34 or equivalent (Figs. 24 and 25) so that the selecting members can act upon needles or jacks before the stitch cam. Different members may be brought into action by the rotation of the controlling drum 12, which is brought about at the end of each stroke by cams 35. For reverse action a switch over cam may be provided, or double sets of carriers one on each side of the cam box or equivalent of the machine may be fitted.

When the pattern mechanism is used to influence needles of the machine, the pattern effect may be produced by tuck stitches or missed stitches or by different coloured 55 yarns, and further, the mechanism may be employed for producing accordion or other particular kinds of fabric. The pattern mechanism may be used for producing reverse plating and for float plating effects.

60 When discs are used, these may be so punched that it would be necessary to render all of them operative to affect every needle in the cylinder. For instance, the discs may be so punched and stacked that one or more 65 series of notches extend throughout the stack

in spiral formation in one direction or in opposite directions.

Diagonal and like patterns may be made by employing driving gear wherein the gear ratio is such that each disc is caused to select 70 different jacks in different e. g. successive revolutions.

It is also possible to produce as many different patterns in the same fabric as there are discs or other selecting members i. e. by 75 constructing and operating the discs or members so that each produces a complete pattern independently of the other or others.

What we claim now is:—

1. For a knitting machine wherein elements are to be controlled for patterning, pattern mechanism comprising a plurality of pattern devices each constituted by a driven rotary member for action selectively upon said elements, and a movable carrier, said carriers being associated so as to form a unitary assemblage in which they are movable individually towards and from the elements to be acted upon, means for selectively moving said carriers whereby the associated members 85 are rendered operative and inoperative in a predetermined manner, and means including a part common to all of said rotary members for rotating same in their carriers.

2. For a knitting machine wherein elements are to be controlled for patterning, pattern mechanism comprising a plurality of pattern devices each constituted by a driven rotary member for action selectively upon said elements, and a movable carrier, 90 said carriers being associated so as to form a unitary assemblage in which they are movable individually towards and from the elements to be acted upon, means for selectively moving said carriers whereby the associated members 95 are rendered operative and inoperative in a predetermined manner, and means including a part common to all of said members for positively driving the same without interfering with the movement of 100 their carriers and their register with the elements influenced thereby.

3. For a knitting machine wherein elements are to be controlled for patterning, pattern mechanism comprising a plurality 105 of devices each constituted by a driven rotary member for action selectively upon said elements, and a movable carrier, said carriers being superimposed co-adjacently for horizontal movement individually to carry said 110 members to and from an operative position, means for moving said carriers selectively whereby the associated members are rendered operative and inoperative in a prearranged manner, and means including a part common 115 to all of said members for rotating same in their carriers.

4. For a knitting machine wherein elements are to be controlled for patterning, pattern mechanism comprising a plurality 120

- of devices each constituted by a driven rotary member for action selectively upon said elements, and a movable carrier, said rotary member having a pattern determining periphery for action upon said elements, the said carriers being superimposed adjacently for horizontal movement individually, mechanism for selectively moving said carriers whereby the associated members are carried to and from an operative position in a predetermined manner, and driving means including a part common to all of said members and adapted positively to drive the latter without interfering with the movement of the carriers.
5. For a knitting machine wherein elements are to be controlled for patterning, pattern mechanism comprising a plurality of rotary discs for action upon said elements, co-adjacent movable carrier plates for said discs respectively for carrying the latter into and out of an active position, and means for moving said plates individually whereby the associated discs can be rendered operative and inoperative in a predetermined manner.
6. For a knitting machine wherein elements are to be controlled for patterning, pattern mechanism comprising a plurality of rotary discs for action upon said elements, co-adjacent movable carrier plates for said discs respectively for moving the latter into and out of an operative position, means for moving said plates individually whereby the associated discs are rendered operative and inoperative in a predetermined manner, and means whereby said discs are positively driven without the drive being interfered with by the movement of said discs into and out of action.
7. For a knitting machine wherein elements are to be controlled for patterning, pattern mechanism comprising a plurality of driven discs for action upon said elements, co-adjacent movable carrier plates for said discs respectively for carrying the latter to and from an operative position, means including a pattern device operative upon said carriers for moving the latter selectively whereby said discs are rendered operative and inoperative in a predetermined manner.
8. For a knitting machine wherein elements are to be controlled for patterning, pattern mechanism comprising a plurality of rotary discs for action upon said elements, co-adjacent movable carrier plates for said discs respectively, means including a pattern device operative upon said plates for selectively moving same to carry the discs to and from an operative position, and means for intermittently actuating the pattern device.
9. For a knitting machine wherein elements are to be controlled for patterning, pattern mechanism comprising a plurality of rotary discs for action upon said elements,

co-adjacent movable carrier plates for said discs respectively, means including a pattern device operable intermittently for moving said plates selectively to carry the associated discs to and from an operative position, and a driving arrangement including a member common to said discs whereby the latter are rotated without the drive being interfered with by their movement into and out of action.

10. For a knitting machine wherein elements are to be controlled for patterning, pattern mechanism comprising a plurality of rotary discs for action upon said elements, co-adjacent movable carrier plates for said discs respectively, for carrying the latter into and out of an active position, and a pattern drum having devices prearranged circumferentially thereon for action upon the plates to selectively move same whereby the associated discs are rendered operative in a predetermined manner, means for intermittently rotating the drum, and spring means for rendering the discs inoperative.

11. For a knitting machine wherein elements are to be controlled for patterning, pattern mechanism comprising a plurality of driven discs for action upon said elements, co-adjacent movable carrier plates for said discs respectively, for carrying the latter into and out of an active position, a pattern drum having devices prearranged circumferentially thereon for action upon the plates to selectively move same whereby the associated members are rendered operative in a predetermined manner, means for intermittently rotating the drum, spring means for rendering the discs inoperative, and a driving arrangement including a member common to the discs whereby the latter are rotated without the drive being interfered with by the movement of the discs into and out of action.

12. In a circular knitting machine having a needle cylinder and independent slidable needles in said cylinder, pattern mechanism comprising a plurality of driven discs for controlling said needles, carriers in which said discs are respectively rotatably mounted, said carriers being arranged co-adjacently and movable individually to carry the associated members into and out of an active position, means including a pattern device operative selectively upon said carriers, whereby the pattern members can be rendered operative and inoperative in a predetermined manner, and means whereby said members are positively driven without the drive being interfered with by the movement of the members into and out of action.

13. In a circular knitting machine having a needle cylinder and independent slidable needles in said cylinder, pattern mechanism comprising a plurality of rotary discs for controlling said needles, co-adjacent movable carrier plates for said discs respectively for carrying the latter into and out of an active position, and a driving arrangement including a member common to said discs whereby the latter are rotated without the drive being interfered with by their movement into and out of action.

moving the latter to and from an active position, means including a pattern device operative upon said plates for selectively moving same whereby the discs can be rendered operative and inoperative in a predetermined manner, and driving mechanism including a member common to the discs whereby the latter are positively driven without the drive being interfered with by the movement of the discs into and out of action.

14. In a circular knitting machine having a needle cylinder and independent slidable needles in the cylinder, pattern mechanism comprising a plurality of rotary discs for controlling the needles, carrier plates superimposed co-adjacently for horizontal movement to carry the discs towards and from the needle cylinder, means including a pattern device adjacent to said plates for moving the latter selectively whereby the discs can be rendered operative and inoperative in a pre-arranged manner, and a driving arrangement including a member common to the discs whereby the latter are driven collectively without the drive being interfered with by the movement of the discs into and out of action.

15. In a circular knitting machine, in combination, a needle cylinder, independent slid-able needles in the cylinder jacks associated with the needles, a cam system for causing said jacks to affect the action of the needles, and pattern mechanism comprising a plu-rality of rotary discs for action upon said jacks, co-adjacent movable carrier plates for said discs respectively, for moving the latter towards and from the jacks, means including a pattern device operative upon said plates for selectively moving same whereby the discs can be rendered operative and inoperative in a prearranged manner, and driving mechanism including a member common to the discs whereby the latter are driven col-lectively without the drive being interfered with by the movement of the discs into and out of action.

16. In a circular knitting machine, in combination, a needle cylinder, independent slid-able needles in said cylinder, jacks in asso-ciation with said needles, a cam system for causing the jacks to affect the action of the needles, and pattern mechanism comprising a plurality of rotary discs for action upon the jacks, carrier plates superimposed co-adjacent-ently for horizontal movement towards and from the needle cylinder, means including a pattern device adjacent to said plates for moving the latter selectively to render the discs operative and inoperative according to requirements, and driving mechanism includ-ing a member common to the discs, whereby the latter are rotated collectively without the drive being interfered with by the movement of the discs into and out of action.

17. For a knitting machine wherein ele-

ments are to be controlled for producing pat-terned fabric, pattern mechanism comprising a plurality of pattern devices each of which consists of a rotary member and a movable carrier therefor, said rotary member hav-ing a pattern determining periphery for ac-tion selectively upon said elements, the said patterning devices being associated with each other so as to form a unitary assemblage in which they are individually movable bodily towards and from the elements to be acted upon by the rotary pattern-determining members, and means for selectively moving said carriers whereby the associated pattern members are rendered operative and inopera-tive in a predetermined manner.

18. For a knitting machine wherein ele-ments are to be controlled for producing pat-terned fabric, pattern mechanism comprising a plurality of pattern devices each of which consists of a rotary member and a movable carrier therefor, said rotary member having a pattern determining periphery for action selectively upon said elements, the said patterning devices being superimposed co-ad-jacently for horizontal movement individual-ly and bodily towards and from the elements to be acted upon by the rotary pattern-de-termining members, and means for selective-ly moving said carriers whereby the asso-ciated pattern members are rendered opera-tive and inoperative in a predetermined manner.

19. For a knitting machine wherein ele-ments are to be controlled for producing pat-terned fabric, pattern mechanism comprising a plurality of pattern devices each of which consists of a rotary member and a movable carrier therefor, said rotary member having a pattern determining periphery for action selectively upon said elements, the said patterning devices being arranged co-adjacently and individually movable bodily towards and from the elements to be acted upon by the rotary pattern-determining members, means for selectively moving said carriers whereby the associated pattern members are carried to and from an operative position in a pre-de-termined manner, and a driving arrangement including a member common to the pattern members whereby the latter are driven with-out the drive being interfered with by the movement of said pattern members into and out of action.

20. In a circular knitting machine in com-bination, a needle cylinder, a series of inde-pendent slidable needles in said cylinder, a series of jacks associated with the needles, a cam system for causing the jacks to affect the action of the needles, and patterning mech-a-nism comprising a plurality of pattern de-vices each of which consists of a rotary mem-ber and a movable carrier therefor, said ro-tary member having a pattern determining periphery for action selectively upon said

5 jacks to determine their engagement with the cam system, the said patterning devices being associated with each other so as to form a unitary assemblage in which they are individually movable bodily towards and from the jacks to be acted upon by the rotary pattern-determining members, and means for selectively moving said carriers whereby the associated pattern members are
10 rendered operative and inoperative in a predetermined manner.

21. In a circular knitting machine, in combination, a needle cylinder, independent slideable needles in the cylinder, jacks associated
15 with the needles, a cam system for causing said jacks to affect the action of the needles, and pattern mechanism comprising a plurality of pattern devices each of which consists of a rotary member and a movable carrier therefor, said rotary member having a pattern-determining periphery for action upon the jacks, the said pattern devices being arranged co-adjacently and individually movable bodily towards and from the jacks,
20 means including a pattern device operative selectively upon said carriers whereby the pattern members are rendered operative and inoperative in a predetermined manner, and means whereby said pattern members are
25 positively driven without the drive being interfered with by the movement of the pattern members into and out of action.

30 In testimony whereof we affix our signatures.

35 THOMAS CHARLES BROMLEY,
ARTHUR SHORTLAND.
